US0D1025099S

(12) **United States Design Patent** (10) Patent No.: US D1,025,099 S
Heffernan et al. (45) Date of Patent: ** Apr. 30, 2024

(54) **DISPLAY SCREEN OR PORTION THEREOF
WITH A GRAPHICAL USER INTERFACE**

H04L 41/22; H04L 12/282; B60H 1/00;
G06T 2200/24; H04M 1/724-72484
See application file for complete search history.

(71) Applicant: **Canva Pty Ltd**, Surry Hills (AU)

(56) **References Cited**

(72) Inventors: **Hannah Heffernan**, Darlinghurst (AU);
Cameron Adams, Rozelle (AU);
Melanie Joy Perkins, Sydney (AU);
Matthew Hardy, Surry Hills (AU);
Martyn Lofberg, Eagle Vale (AU);
Matthew David Anderson, Newport (AU)

(73) Assignee: **CANVA PTY LTD**, Surry Hills (AU)

(**) Term: **15 Years**

(21) Appl. No.: 29/855,473

(22) Filed: **Oct. 3, 2022**

Related U.S. Application Data

(62) Division of application No. 29/786,150, filed on May 28, 2021, now Pat. No. Des. 969,145, which is a division of application No. 29/746,574, filed on Aug. 14, 2020, now Pat. No. Des. 923,651, which is a division of application No. 29/647,439, filed on May 12, 2018, now Pat. No. Des. 896,248.

CLAIM

The ornamental design for a display screen or portion thereof with a graphical user interface, substantially as shown and described.

DESCRIPTION

The patent or application file contains at least one drawing executed in color. Copies of this patent or patent application publication with color drawing(s) will be provided by the Office upon request and payment of the necessary fee.

The single view is a front view of a display screen or portion thereof with a graphical user interface.

The outermost dot-dash broken lines illustrate a display screen or portion thereof and form no part of the claimed design. The remaining dashed broken lines (i) show text in the drawing that illustrates portions of the graphical user interface that form no part of the claimed design and (ii)

illustrate and enclose faded portions of the graphical user interface that form no part of the claimed design.
